TICKET STRIP AND TICKET

Benjamin H. Freedman, New York, N. Y.

Application December 19, 1944, Serial No. 568,887

6 Claims. (Cl. 283—53)

1

This invention relates to ticket strips in general, and more especially to ticket strips having parallel longitudinally extending stub areas from which tickets are cut in various lengths to correspond to one, two, or more ticket unit areas or admissions.

The tickets heretofore in use, particularly of the type having parallel longitudinally extending stub areas, where the stub areas of subsequently formed tickets are separated from one another for the convenience of the ticket taker and patron, it has been conventional to form a longitudinally extending weakened line to facilitate dividing the ticket into its stub areas. It has also been conventional where the ticket strip was dispensed from a ticket dispensing machine, such as disclosed in Patent No. 2,361,392, issued October 31, 1944, to form the feed pin holes in the longitudinally extending weakened line and along the division between successive ticket unit areas and to fanfold the strip before threading it into the ejecting mechanism along the division between at least two successive ticket unit areas. The formation of the longitudinally extending weakened line as aforesaid was intended to facilitate dividing the tickets after issue into their respective stub areas; the formation of the feed pin holes at the intersection of the division between the stub areas and the divisions between successive ticket unit areas was to facilitate the doorman or ticket taker, particularly at night or in a poorly lighted lobby of a moving picture theatre to spot the division between the adjacent stub areas and also the division between the successive ticket unit areas; and the formation of fanfolds along divisions between two successive ticket unit areas was dictated in part by the ease with which the tickets could be fanfolded at such divisions due to the feed pin holes formed at such divisions.

The disadvantages that resulted from these practices were many. As an instance, due to the formation of the feed pin holes on the weakened line defining the longitudinally extending stub areas from one another, if any slight accidental resistance was offered during the feed of the strip by the feed pins, the weakened line would part and permit the feed pins to move through such part without properly feeding the strip. In turn, due to the fanfold on the division between successive ticket unit areas, and the upsetting of the fibers in the paper or ticket stock at such fanfolds, the ticket cutting knife for cutting off the desired one, two or three ticket unit when attempting to cut the ticket at said upset fanfold would frequently jam or cause a strip to be caught and interfere with the proper functioning of the ejecting mechanism.

In view of the foregoing, and with a view to overcoming, amongst others, the objections here-

2

tofore noted, it is an object of the present invention to provide an improved strip of tickets and in turn the resulting improved ticket unit area, characterized by a strip having a longitudinally extending weakened line defining the stub areas from one another, but with the feed pin holes removed from said weakened line, and in turn to fanfold the strip along laterally extending lines that do not register with the divisions between successive ticket unit areas.

10 It is another object of the present invention to provide as an article of manufacture a ticket strip that is fanfolded in staggered relation so that the fanfolds, being naturally more bulky than the other overlapping portions of the ticket strip, will not be disposed in a common line, and thus facilitate accommodating a longer strip in a given container in the interest of conserving space.

15 It is still another object of the present invention to provide an improved ticket strip of the character heretofore set forth having two parallel longitudinally extending rows of stub areas, defined from one another by a weakened line but with a plurality of feed pin holes, at least two in number removed from the longitudinally extending line, but in a transversely extending lateral line.

20 These and other features, capabilities and advantages of the invention will appear from the subjoined detail description of specific embodiments thereof illustrated in the accompanying drawings in which

25 Fig. 1 is a perspective of a strip of tickets before being cut into ticket areas but fanfolded in accordance with one feature of the present invention.

30 Fig. 2 is a fragmental perspective of another embodiment of a strip of tickets fanfolded in accordance with one feature of the present invention.

35 Fig. 3 is a fragmental plan view of a strip made in accordance with the embodiment illustrated in Fig. 2.

40 Fig. 4 is a fragmental plan view of another embodiment of the strip.

45 Fig. 5 is a fragmental plan view of still another embodiment of the strip.

50 Fig. 6 is a fragmental perspective of a strip made according to the embodiment illustrated in Fig. 4 and fanfolded according to one feature of the present invention.

55 Fig. 7 is a fragmental perspective of a strip made according to the embodiment illustrated in Fig. 5.

60 Fig. 8 is a plan view of a one unit ticket separated from a strip of the type shown in Fig. 7.

Fig. 9 is a plan view of a two unit ticket separated from a strip of the type shown in Fig. 7.

65 Fig. 10 is a plan view of one of the stub areas

after it has been separated from a two unit ticket such as disclosed in Fig. 9.

In the embodiment shown in Fig. 1, there is a strip 1 of the type to be fed through a ticket issuing machine such as disclosed in Patent No. 2,361,392 dated October 31, 1944, having parallel stub areas 2 and 3 preferably defined from one another by a weakened line such as the line 4 formed as an instance by perforations, indentations or the like. In the present instance, the successive ticket unit areas 5 have similar printed matter on each, such as the name of the theatre, city in which the theatre is located, and price, indicated as 30¢ in the case of the strip shown in Fig. 1. Aside from such similar printed matter, the successive ticket areas may have consecutive serial numbers to aid in determining the number of tickets that have been dispensed, the first ticket unit to be dispensed of this strip 1 bearing the number 664,321. Heretofore it has been conventional when the strip 1 was intended to be dispensed with a ticket ejecting machine such as disclosed in Patent No. 2,361,392 to form a feed pin opening substantially along the middle of the strip 1 and in some instances directly on the weakened line 4, and along the division between two successive ticket unit areas 5, 5, as shown in Fig. 1, see the feed pin openings 6.

Furthermore, to aid the accounting or auditing department in sorting and counting the tickets, the stub areas 2 and 3 are distinguished from one another by some suitable marking such as color, according to the price or use of the ticket being dispensed. Any combination of colors can be used. As an instance, blue can be used for tickets of the 30¢ denominations, red for those of the 50¢ denominations, and so forth. In the present instance, the stub areas 2 are illustrated as bearing the color red and the stub areas 3 are left in blank, illustrative of bearing the color white. Preferably the border 1 of the stub area 3 bears the same color as that of the stub area 2, known in the trade as bleeding over into the area 3, from the area 2. Thereby, should the stub area 2 be retained by the patron, and stub area 3 taken up by the ticket taker, the collector could easily separate the 30¢ stub areas from the 50¢ stub areas by the border markings 7. According to the present invention, however, the strip instead of being folded on the division between successive ticket areas 5 is folded along a line disposed between such divisions, possibly in the middle of a ticket unit area 5. To facilitate splicing a successive ticket strip to one being dispensed, it has long become conventional to fanfold the strips 1 rather than form them in rolls on account of the difficulty of splicing a successive strip on to one being dispensed if it is formed in a roll. However, when so fanfolded due to the upsetting of the ticket stock at the folds, the ticket containers can only hold a limited supply and a large amount of unused space in the ticket containers is wasted. It has been found, however, that when the fanfolds are staggered, even while a small amount of space at the end is wasted, a much longer strip 1 can be accommodated in each ticket container. While any number of different staggered arrangements may be used without departing from the general spirit of the invention, one arrangement is disclosed as illustrative of this feature of the invention, in which, see Fig. 1, the successive cyclical groups each are composed of eight sections, 8, 9, 10, 11, 12, 13, 14 and 15 of the strip 1, and are fanfolded one upon the other, the section 8 con-

taining ten ticket unit areas, the section 9 containing nine ticket unit areas, the section 10 containing ten ticket unit areas, the section 11 containing nine ticket unit areas, the section 12 containing ten ticket unit areas, the section 13 containing eleven ticket unit areas, the section 14 containing ten ticket unit areas, and the section 15 containing eleven ticket unit areas.

Furthermore, each fold is formed intermediate the divisions between the ticket unit areas 5, see the folds 16, at the right hand side of the strip 1. When the folds 16 are so positioned, then the disadvantage now encountered when the cutting knife (not shown) is required to separate a ticket along such upset fold is avoided. Heretofore as aforesaid, frequently the ticket discharge machines became jammed when the knife was required to sever a ticket along this upset fold. The upset portion of the ticket stock at such fold is generally thicker than the remainder of the ticket stock and consequently if the knife is adjusted at a given speed for severing a ticket stock portion, not so upset, a different resistance of course is encountered when it engages the ticket stock where the fold has upset it.

In Figs. 2 and 3, the ticket strip 17 there shown is similar to the ticket strip 1, except that the feed pin openings 18 are spaced from the weakened line 19. A decided advantage flows from this arrangement. As an instance, if any undue resistance were encountered by the feed pins (not shown) if the feed pin openings are disposed on the weakened line as is the case with the openings 6 in the embodiment of Fig. 1, frequently the feed pin would tear the strip, the path of least resistance of course being the weakened line, as an instance along the weakened line 4, and then cause the strip feed to be thrown out of alignment. With the arrangement shown in Figs. 2 and 3, with the weakened line 19 not intersecting the openings 18, the tendency to tear the ticket along these weakened lines is, of course, avoided and a more positive feed thereby insured.

With the embodiment shown in Figs. 4 and 6, advantage is taken of the fact that the feeding force can, of course, be distributed when more than one feed pin opening is provided, particularly when a plurality, two or more feed pins, engage the ticket strip simultaneously along a transversely extending area. In view thereof, the strip 20 disclosed in Figs. 4 and 6 is provided with a succession of pairs of openings 21 and 22, the openings 21 of the successive pairs being in alignment with one another, and in turn the openings 22 of the successive pairs being in alignment with one another but neither aligned row of openings 21 nor aligned row of openings 22 being formed along the weakened line 23 provided to facilitate separating the stub areas from one another.

In the embodiment shown in Figs. 5, 7, 8, 9 and 10 a ticket strip 24 is shown in which in addition to a succession of pairs of openings 25 and 26, there are provided the recesses 27 along the longitudinally extending edges of the strip and the central row of openings 29 in alignment with one another. Along the division between each two successive ticket unit areas, to aid the ticket taker in dividing the ticket unit areas along such transversely extending line, there will then be found a row of interruptions in the ticket strip, including a recess 27, openings 25, 29 and 26 and a recess 28 in the order named.

It is of course understood that the best results can be obtained with the strips shown in Figs.

2, 6 and 7 when they are folded along intermediate divisions between successive ticket unit areas as shown.

While not necessary, nevertheless it is desirable to point out that excellent results have been obtained when the openings 6 and 18 of the embodiments illustrated in Figs. 1 and 2, respectively, have each a diameter approximating from three-sixteenths of an inch to one-quarter of an inch, when the openings 21 and 22 of the embodiment illustrated in Figs. 4 and 6 and the feed pin receiving openings 25 and 26 of the embodiment illustrated in Figs. 5 and 7 approximate five-thirty-seconds of an inch, and when the recesses 27 and 28 and the central openings 29 approximate one-eighth of an inch in diameter.

It is obvious that various changes and modifications may be made to the details of construction without departing from the general spirit of the invention set forth in the appended claims.

I claim:

1. A ticket strip having a longitudinally extending weakened line defining two longitudinally extending stub areas and having printed matter to define successive ticket unit areas, there being feed pin openings along the division between successive ticket unit areas to facilitate determining the successive ticket unit areas from one another, and folds in said strip intermediate the divisions between successive ticket unit areas, the folds being formed in cyclical groups, each group consisting of a plurality of sections of said strip, each section in turn consisting of a plurality of successive unit areas between successive folds, and each section varying successively in length.

2. A ticket strip having a longitudinally extending weakened line defining two longitudinally extending stub areas and having printed matter to define successive ticket unit areas, there being feed pin openings along the division between successive ticket unit areas to facilitate determining the successive ticket unit areas from one another, and folds in said strip intermediate the divisions between successive ticket unit areas, the folds being formed in cyclical groups, each group consisting of eight sections of said strip, each section in turn consisting of a plurality of successive unit areas between successive folds, and each section varying successively in length.

3. A ticket strip having a longitudinal extending weakened line defining two longitudinally extending stub areas and having printed matter to define successive ticket unit areas, there being feed pin openings along the division between successive ticket unit areas to facilitate determining the successive ticket unit areas from one another, and folds in said strip intermediate the divisions between successive ticket unit areas, the folds being formed in cyclical groups, each group consisting of eight sections of said strip, each section in turn consisting of a plurality of successive unit areas between successive folds, and each section varying successively in length, the successive sections of each group corresponding to ten, nine, ten, nine, ten, eleven, ten and eleven ticket unit areas, respectively.

4. A ticket strip having a longitudinally extending weakened line defining two longitudinally extending stub areas and having printed matter to define successive ticket unit areas, there being feed pin openings along the division be-

tween successive ticket unit areas to facilitate determining the successive ticket unit areas from one another, and folds in said strip intermediate the divisions between successive ticket unit areas, the folds being formed in cyclical groups, each group consisting of a plurality of sections of said strip, each section in turn consisting of a plurality of successive unit areas between successive folds, and each section varying successively in length, said feed pin receiving openings being spaced from the longitudinally extending weakened line.

5. A ticket strip having a longitudinally extending weakened line defining two longitudinally extending stub areas and having printed matter to define successive ticket unit areas, there being at least two feed pin openings along the division between successive ticket unit areas, but spaced from the longitudinally extending weakened line to facilitate determining the successive ticket unit areas from one another without presenting a weakened area to the feed pins, and folds in said strip intermediate the divisions between successive ticket unit areas, the folds being formed in cyclical groups, each group consisting of a plurality of sections of said strip, each section in turn consisting of a plurality of successive unit areas between successive folds, and each section varying successively in length.

6. A ticket strip having a longitudinally extending weakened line defining two longitudinally extending stub areas and having printed matter to define successive ticket unit areas, there being two feed pin openings along the division between successive ticket unit areas but spaced from the longitudinally extending weakened line, also openings at the intersection between said longitudinally extending weakened line and the divisions between successive ticket unit areas, and recesses at the edges of the strip at the ends of the divisions between successive ticket unit areas to facilitate determining the successive ticket unit areas from one another without presenting a weakened area to the feed pins with the accompanying danger of jamming the ticket dispensing machine should an unintentional resisting force cause the feed pin to tear along the weakened line while disposed in a feed pin receiving opening, and folds in said strip intermediate the divisions between successive ticket unit areas, the folds being formed in cyclical groups, each group consisting of a plurality of sections of said strip, each section in turn consisting of a plurality of successive unit areas between successive folds, and each section varying successively in length, said feed pin receiving openings being spaced from the longitudinally extending weakened line.
